(57) **CLAIM**

The ornamental design for an IV spike with multi-port tubing adapter, as shown and described.

DESCRIPTION

FIG. 1 is a front perspective view of an IV spike with multi-port tubing adapter according to the present design; FIG. 2 is a rear perspective view of the IV spike with multi-port tubing adapter of FIG. 1;

FIG. 3 is a front view of the IV spike with multi-port tubing adapter of FIG. 1;

FIG. 4 is a rear view of the IV spike with multi-port tubing adapter of FIG. 1;

FIG. 5 is a right side view of the IV spike with multi-port tubing adapter of FIG. 1;

FIG. 6 is a left side view of the IV spike with multi-port tubing adapter of FIG. 1;

FIG. 7 is a top view of the IV spike with multi-port tubing adapter of FIG. 1; and,

FIG. 8 is a bottom view of the IV spike with multi-port tubing adapter of FIG. 1.

The broken lines show portions of the design that form no part of the claimed design.

1 Claim, 6 Drawing Sheets
